US00D755414S

(12) **United States Design Patent**
Taylor

(10) **Patent No.:** **US D755,414 S**
(45) **Date of Patent:** **** May 3, 2016**

(54) **LED LAMP**

- (71) Applicant: **TADD, LLC**, Cary, IL (US)
(72) Inventor: **Timothy Taylor**, Barrington, IL (US)
(73) Assignee: **TADD, LLC**, Cary, IL (US)
(**) Term: **14 Years**

(21) Appl. No.: **29/517,391**(22) Filed: **Feb. 12, 2015**(51) **LOC (10) Cl.** **26-04**(52) **U.S. Cl.** **USPC** **D26/2**(58) **Field of Classification Search**

Primary Examiner — Ian Simmons*Assistant Examiner* — Harold Blackwell, II(74) *Attorney, Agent, or Firm* — Clark Hill PLC; James R. Foley(57) **CLAIM**

The ornamental design for an LED lamp, as shown and described.

DESCRIPTION

FIG. 1 is a perspective view of the LED lamp;

FIG. 2 is a side view thereof;

FIG. 3 is a top view thereof; and,

FIG. 4 is a bottom view thereof.

The broken lines in the drawings are included for the purpose of illustrating unclaimed portions of the LED lamp and form no part of the claimed design.
